US00D946716S

(12) **United States Design Patent** (10) **Patent No.:** **US D946,716 S**
(45) **Date of Patent:** **** Mar. 22, 2022**

(54) **MECHANICAL COUPLER**

(71) Applicant: **MCS Industries, Inc.**, Easton, PA (US)

(72) Inventors: **Geoffrey William Bastian**, Wind Gap, PA (US); **Michael Lee Pyle**, Sugar Grove, IL (US); **Matthew Scott Kressin**, Allentown, PA (US); **Robert Terry Coyle, Jr.**, Palmer, PA (US)

(73) Assignee: **MCS Industries, Inc.**

(**) Term: **15 Years**

(21) Appl. No.: **29/757,022**

(22) Filed: **Nov. 2, 2020**

Related U.S. Application Data

(60) Continuation of application No. 29/729,046, filed on Mar. 24, 2020, now Pat. No. Des. 904,168, which is a division of application No. 29/661,111, filed on Sep. 25, 2018, now Pat. No. Des. 882,384.

CLAIM

The ornamental design for a mechanical coupler, as shown and described.

DESCRIPTION

FIG. 1 is a top perspective view of a mechanical coupler according to our new design;

FIG. 2 is a bottom perspective view thereof;

FIG. 3 is a front view thereof, the rear view being identical to the front view;

FIG. 4 is a right-side view thereof, the left-side view being identical to the right-side view;

FIG. 5 is a top view thereof; and,

FIG. 6 is a bottom view thereof.

The broken lines illustrate portions of the mechanical coupler that form no part of the claimed design.

1 Claim, 5 Drawing Sheets
